UNITED STATES PATENT OFFICE.

JOHN HOEY, OF NEW YORK, N. Y.

MILK-BOTTLE RECEPTACLE.

1,229,268.

Specification of Letters Patent. Patented June 12, 1917.

Application filed August 28, 1916. Serial No. 117,317.

To all whom it may concern:

Be it known that I, JOHN HOEY, a citizen of the United States, residing at New York, in the county of New York and State of New York, have invented new and useful Improvements in Milk-Bottle Receptacles, of which the following is a specification.

This invention relates to receptacles which are adapted to be attached to the door of a dwelling for receiving goods of any description such as milk bottles or the like.

The chief characteristic of this invention is to provide a device of this character which is so constructed and so arranged upon a door as to prevent unauthorized persons from pilfering the receptacle or the contents thereof.

Another object of this invention is to provide a device of the above described character which is of simple, durable and efficient construction and which may be readily attached or detached from a door of any common construction without defacing the door or door frame in any manner.

Other objects of the invention will appear as the specification is read in connection with the accompanying drawings, in which:—

Figure 1 is a side elevation of the device constructed in accordance with my invention.

Fig. 2 is an end elevation of the device.

Fig. 3 is a horizontal sectional view of the device showing the same in applied position upon a door.

Referring to the drawings in detail, my invention comprises a metallic receptacle 1 which is preferably of rectangular formation, its upper end being open and adapted to be closed by a lid 2 which is hingedly connected to the receptacle as at 3. The lid 2 is provided with a keeper 4 which is adapted to coöperate with a latching means 5 formed upon the receptacle whereby the lid may be held in locked position. In this instance I have used a spring actuated latch which is adapted to automatically lock the lid in closed position upon the receptacle as will be understood.

The receptacle 1 is provided upon one of its faces at a point adjacent the lower edge thereof with a laterally extending plate 6 which is preferably of a width slightly greater than the thickness of the average door and is provided with a metal strip 7

upon its upper face and preferably adjacent its free longitudinal edge. In this instance I have shown the strip of rectangular formation in cross section and coextensive of the plate.

Arranged upon one vertical edge of the receptacle and at one of the sides which is adjacent the side upon which the plate 6 is formed, is a vertically disposed plate 8, the same extending laterally from the receptacle in the same direction as that of the plate 6 as at 9 whereupon it is bent at right angles and extended in a direction away from the receptacle as at 10. The plate is then bent again at right angles as at 11 in a direction opposite to the first right angularly bent portion whereupon it is extended for an appreciable distance to correspond to the thickness of the door as is clearly shown in the drawings. The plate 8 is provided upon its inner face at a point adjacent the vertical free edge thereof with a vertically extending strip 12, this strip being formed of metal and preferably rectangular in cross section as is the strip 7.

In operation, the receptacle is placed upon the outer side and contiguous to the door by inserting the plate 6 beneath the door, the strip 7 and the adjacent side wall of the receptacle forming guide ways for the door and preventing lateral movement of the receptacle with relation to the door. The receptacle is moved transversely of the door until the vertical edge of the door engages the plate 8, when the vertical edge of the door will be snugly engaged by the angular bent portion of the plate 8 while the strip 12 will be disposed upon the inner side edge of the door and will engage the door to prevent the receptacle from being removed from the door. It is to be understood that when the receptacle is applied to the door, the latter is in open position and after having properly positioned the receptacle as has been described, the door is moved to closed position whereby the plate 8 will have engaged the jamb or casing of the door, it being noted that the plate is offset with relation to the receptacle whereby the plate 8 will conform to the angle of the door jamb to permit the proper closing of the door. When the door is in closed position as shown in Fig. 3, it will be seen that the receptacle is securely locked against removal upon the

door and that it will be impossible to remove the receptacle only when the door is in open position.

It will be manifest from the foregoing that 5 I have provided a simple and efficient means for securely locking the receptacle upon the door, the delivered goods being placed within the receptacle and the lid moved to closed position whereupon the same will be locked 10 as will be understood. Thus the goods such as milk bottles or the like may be safely delivered to the exterior of a dwelling without the liability of having the same pilfered.

It is thought from the foregoing taken in 15 connection with the accompanying drawings, that the construction and operation of my device will be apparent to those skilled in the art, that minor changes in the size, shape, proportion and minor details of construction 20 may be made without departing from the spirit and scope of the appended claims.

What I claim is:—

1. A receptacle adapted to be mounted 25 upon a door and having means formed on one bottom edge thereof and engageable with the bottom edge of the door, and means formed on one vertical edge and engageable

with the free vertical edge of the door for locking the receptacle upon the door when the latter is in closed position.

2. In combination a receptacle, laterally extending plates formed upon two of the adjacent edges of the receptacle and disposed at right angles to each other, the plate upon the vertical edge being L-shaped and offset 35 from the receptacle, and strips secured to each of the plates.

3. A device of the class described comprising a receptacle having a hinged lid, means for locking the lid in closed position, 40 laterally extending plates formed on the receptacle and disposed at right angles with relation to each other, and strips formed on the confronting faces of the plates.

4. In combination, a rectangular receptacle, a laterally extending plate formed on one bottom edge thereof, a second laterally extending plate formed on one vertical edge of the receptacle at the same side as the first plate, and strips formed on each of the 50 plates.

In testimony whereof I affix my signature.

JOHN HOEY.

Copies of this patent may be obtained for five cents each, by addressing the "Commissioner of Patents, Washington, D. C."
